INVENTOR.

George E. Adams

UNITED STATES PATENT OFFICE.

GEORGE E. ADAMS, OF PROVIDENCE, RHODE ISLAND.

BAR FOR JEWELRY-CHAINS.

SPECIFICATION forming part of Letters Patent No. 288,392, dated November 13, 1883.

Application filed March 26, 1883. (No model.)

To all whom it may concern:

Be it known that I, GEORGE E. ADAMS, of the city and county of Providence, in the State of Rhode Island, have invented a new and useful Improvement in Bars for Attachment to Watch-Chains and other Articles of Jewelry, of which the following is a specification, reference being had to the accompanying drawings.

My invention relates to bars for chains, sleeve links, buttons, and other articles. The bar is composed of metal or other proper material. It may be grooved or slotted from end to end, or from the center, or near the center, to one end thereof, as desired. No end grooves or slots are necessary. Preferably, two slots or grooves are made upon opposite sides of the bar, in which an eye or catch is secured in such manner that it may be moved through the entire length of the slots or grooves to or near the end of the bar, and turned parallel or nearly parallel therewith. Any other mechanical devices for the extension of the eye as aforesaid may be used.

Figure 1 is a side view of the bar with the eye in position. Fig. 2 is a transverse section on the line $\alpha\alpha$ of Fig. 1. Figs. 3 and 4 are similar sections illustrating modifications in the form of the bar and its attachments.

In the accompanying drawings, A is the bar; B, the ring; C, the eye; D, the catch; D', the ends of the catch; E, the slots; a, the grooves; b, the spring. The bar may be composed of metal or other suitable material. It is of any desired shape—preferably cylindrical or tubular. The sides of the bar may be struck up from any suitable material in two or more parts or otherwise, as desired. The slots or grooves may be produced directly opposite each other on opposite sides of the bar, as in Figs. 1, 2, and 3, or elsewhere upon the circumference, leaving between them, if desired, but a narrow strip of material, as in Fig. 4. The slot need not be extended to the end of the bar. (See Fig. 1.) The eye, however, is of such a size and shape that it may easily be passed over the end of the bar when passed to the end of the slot.

The spring is composed of steel or other suitable material, and may be secured to the slotted end of the bar and made to extend to

or beyond the other end of the slot, in such manner that it constantly exerts an upward pressure upon the under surface of the eye when the latter is within its bearings at the center of the bar within the slots aforesaid; 55 or the spring may be fastened in any manner which will secure the pressure aforesaid. After the slots have been produced and the spring secured as desired, the parts are fastened together by soldering or otherwise. If, 60 when the sides of the bar are fastened together, apertures are left at the ends, end pieces adapted for such use are fitted and fastened therein.

The eye is held securely in its position in 65 the center of the bar within notches or upward extensions of the slots. It is detached therefrom by taking the eye or ring between the thumb and finger and pressing the same down upon the spring. If grooves are used, 70 slight depressions may be made in the ends thereof in the center of the bar, designed to receive the ends D' of the catch D. The catch, being composed of steel or other suitable flexible material, is easily sprung in and out of the 75 depressions. The eye and ring may be integral, extending on the same line or plane. (See drawings.)

The chief point in my invention consists in detaching an eye, ring, link, or other appendage of a jewelry-bar from its natural and proper position at or near the center of the bar, moving the same to or near the end, and extending the same beyond the end thereof, parallel or nearly parallel therewith, whether such result 85 be secured by the use of grooves, slots, or other devices, excepting, however, the devices specified in Letters Patent of the United States No. 273,792.

A jewelry-bar as thus constructed is much 90 better adapted for most uses than those in ordinary use. It may be easily inserted in an aperture scarcely larger than the bar itself, while an ordinary bar requires a much larger aperture. It is particularly adapted for link 95 cuff-buttons, as its exposed surface is smooth and free from rings or bands or other contrivances for securing the eye or ring, and is susceptible of a high degree of polish or ornamentation. It makes a more finished cuff-fastener 100

than the link-buttons in ordinary use, as the small apertures in the cuffs designed for the reception of the buttons are covered and hidden thereby.

5 I claim and desire to secure by Letters Patent—

1. A jewelry-bar having a movable eye attached at or near the center of said bar, and capable of being moved to or near the end thereof and extended parallel or nearly parallel therewith, substantially as described.
- 10 2. The combination, with the bar A, having

slots E E, of the eye C, arranged in said slots, and capable of being moved through the same to or near the end of the bar, and the spring b, 15 secured within the bar, and adapted to hold the eye at or near the center of the bar by exerting a pressure against the under side of said eye, substantially as described.

GEO. E. ADAMS.
